United States Patent Office.

HENRY S. DRAPER, OF ROCHESTER, NEW YORK.

Letters Patent No. 95,209, dated September 28, 1869; antedated September 13, 1869.

IMPROVED MEDICAL EXTRACT.

The Schedule referred to in these Letters Patent and making part of the same.

To all whom it may concern:

Be it known that I, HENRY S. DRAPER, of Rochester, in the county of Monroe, and State of New York, have invented or discovered a new and useful Extract for Medicinal Uses; and I do hereby declare the following to be descriptive thereof, which will enable others skilled in the art to which my invention appertains, to fully understand and use the same.

In carrying out my invention, I make use of the leaves, bark, root, covering, or coating of the shell of the nut and the wood of the black walnut tree, either separately or in combination.

For this purpose I strip the leaves or bark from the tree, or cut up the wood or the outer coating of nutshell, and place either or all in a suitable kettle or boiler, with a quantity of rain-water, in the proportion of about one pound of the coating of the shell, or of about two pounds of leaves, bark, or root, to about four gallons of rain-water, and boil the mass until it leaves about one gallon, or until it attains the desired color, by which I am governed in concluding that the extract is of the proper strength.

The compound is then allowed to cool, after which it is strained, and then bottled, and is now ready for use.

Or I place the ingredients in a retort, and cause them to undergo the process of distillation, and the product be collected in a receiver, in any well-known manner, and be treated as in the former case.

In the external application of the extract, I rub the affected parts thoroughly with small quantities thereof, as long as desired, or until relief is afforded. During this operation the patient may feel more or less pain, but this is the action of the extract, and will sooner or later cease, and with it the cure is complete.

For internal application, I suggest three to ten drops, according to the nature of the case.

The extract is remedial in cases of rheumatism, neuralgia, warts, corns, bunions, chilblains, inflammations, sore feet, and all aches and pains generally.

What I claim as new, and desire to secure by Letters Patent, is—

The within-described extract, as a new and useful medicine for the purposes set forth.

To the above specification of my discovery, I have signed my name, this 25th day of January, 1869, in the presence of two subscribing witnesses.

HENRY S. DRAPER.
